COMBINED CHAIR AND HAIR DRYER

De Witt Y. Gorman, Houston, Tex., assignor to
D. Y. Gorman, Houston, Tex.

Filed Mar. 24, 1961, Ser. No. 64,468

Term of patent 14 years

(Cl. D15—3)

FIG. 1 is a perspective taken from a point in front and to one side of a combined chair and hair dryer embodying this design;

FIG. 2 is a side view of the combined chair and hair dryer;

FIG. 3 is a view directly of the front of the combined chair and hair dryer; and

FIG. 4 is a view directly from the rear of the combined chair and hair dryer.

My design comprises a one-piece, molded armchair body positioned upon relatively short legs, having an adjustable hooded hair dryer attached to the highest point of the curved back, together with a coin-operated switch imbedded in the front of one of the arms, substantially as shown.

I claim:

The ornamental design for a combined chair and hair dryer, as shown and described.
